DESIGN FOR A WATCH

Marc Didisheim, La Chaux de Fonds, Switzerland

Application June 18, 1940, Serial No. 93,084

Term of patent 7 years

To all whom it may concern:

Be it known that I, Marc Didisheim, a citizen of Switzerland, residing at La Chaux de Fonds, Canton of Neuchatel, Switzerland, 67 rue Numa Droz, have invented a new, original, and ornamental Design for a Watch, of which the following is a specification, reference being had to the accompanying drawing, forming a part thereof.

Figures 1 and 2 are, respectively, a front and rear face view of the watch showing my new design; Figure 3 is a lateral view thereof, and Fig. 4 is a partial sectional view along the line A—A of Fig. 2.

I claim:

The ornamental design for a watch, as shown.
MARC DIDISHEIM.
